UNITED STATES PATENT OFFICE

95,094

DESIGN FOR A MEMORIAL

Joseph B. Ullman, Washington, D. C.

Application January 23, 1935, Serial No. 54,997

Term of patent 3½ years

To all whom it may concern:

Be it known that I, Joseph B. Ullman, a citizen of the United States, residing at Washington, in the District of Columbia, have invented a new, original, and ornamental Design for Memorials, of which the following is a specification, reference being had to the accompanying drawing, forming a part thereof.

The figure is a perspective view of a memorial, showing my new design.

I claim:

The ornamental design for a memorial, as shown.

JOSEPH B. ULLMAN.
